(57) **CLAIM**

I claim the ornamental design for the game call assembly, as shown and described.

DESCRIPTION

FIG. 1 is an exploded view of an embodiment of a game call assembly showing my new design;

FIG. 2 is a perspective view thereof;

FIG. 3 is a top plan view thereof;

FIG. 4 is a side elevation thereof;

FIG. 5 is an end view thereof;

FIG. 6 is an end view thereof opposite that shown in (FIG. 5);

FIG. 7 is a top plan view of a first portion thereof;

FIG. 8 is a side plan view thereof;

FIG. 9 is an end view thereof;

FIG. 10 is an end view thereof opposite that shown in (FIG. 9);

FIG. 11 is a top plan view of a second portion thereof;

FIG. 12 is a bottom plan view thereof;

FIG. 13 is a end view thereof; and,

FIG. 14 is a side view thereof.
